UNITED STATES PATENT OFFICE.

SIMON LIBROS, OF CYNWYD, PENNSYLVANIA, ASSIGNOR OF ONE-HALF TO OSCAR LIBROS, OF PHILADELPHIA, PENNSYLVANIA.

SIGN.

Application filed November 26, 1924. Serial No. 752,308.

To all whom it may concern:

Be it known that I, SIMON LIBROS, a citizen of the United States, residing at Cynwyd, in the county of Montgomery and State of Pennsylvania, have invented certain new and useful Improvements in Signs, of which the following is a specification.

This invention relates to display signs and more particularly to illuminated signs in which the display matter is to be changed from time to time as for instance in the display of theater programs.

Signs of this general type have been developed but they have been ordinarily subject to one or more disadvantages such as complication and expense of structure, inaccessibility of the advertising matter for quick change and the ineffective distribution and loss of the light.

It is the primary object, therefore, of the invention to provide a display sign which is of simple and inexpensive construction, which is easy to assemble and the display matter of which can be readily changed. I propose an arrangement whereby I can largely use parts of standard commercial manufacture.

A more specific object of the invention is the provision of a display sign in which the display matter may be locked securely against displacement by unauthorized persons and in which the insertion opening may be effectively sealed whereby substantially all of the light is made effective for illuminating the sign.

Another object of the invention is to provide in a device of the character described, an improved arrangement of parts for securing more effective and uniform distribution of light.

Still another object is to provide an arrangement whereby the lighting elements can be disposed marginally of the display matter to eliminate glare while still keeping overall dimensions within small limits.

With the foregoing and related objects in view, the invention consists in the novel construction, combination and arrangement of parts hereinafter described and claimed.

In the accompanying drawings illustrating my invention,

Fig. 1 is a face view of the device, dis-

play matter being indicated in several of the guide-ways;

Fig. 2 is an edge view of Fig. 1 looking toward the left;

Fig. 3 is a front view with the display panel or lid removed and having a portion broken away for clarity;

Fig. 4 is an enlarged section taken on the line 4—4 of Fig. 3 with the central portion broken out;

Fig. 5 is a plan section taken on the line 5—5 of Fig. 1 with the central portion broken out;

Fig. 6 is a plan section taken on the line 6—6 of Fig. 1;

Fig. 7 is an enlarged vertical section of the display panel or lid with a portion broken out;

Fig. 8 is a plan section taken on the line 8—8 of Fig. 7.

Referring to the drawings, the reference character A designates a casing in general, B a display panel or lid, and C a plurality of internal illuminating elements.

The casing A is of very simple character and is here shown of pressed metal construction, box-like in form and having its front side 1 open. The casing is stiffened along its vertical edges 2 adjacent its open front by bending the metal into substantial channel shape in cross-section which also serves to present a smooth surface to the panel B as it is slid into place. The upper and lower edges 3 and 4 respectively, are similarly formed, thereby stiffening the casing along such edges. It will be seen however that the upper edge portion 3 is first bent upward and then in to channel form, thus providing a guide-way for complementary means carried on the panel B to be hereinafter described, while the lower edge portion 4 is first bent downward and then into channel form thus providing a similar guide-way for the panel at this point. Braces 5 are provided at the corners of the casing to further stiffen it.

The panel B is provided adjacent its upper and lower edges with the members 6 and 7 of substantial channel section extending crosswise of the panel, which members may be secured thereto in any convenient manner. These members are complemen-

tary to and cooperate with the channel portions 3 and 4 on the casing A to hold the panel to the casing, yet permitting it to slide laterally with respect to the casing. 5 Thus by sliding the panel on the guide-ways access may be had to the interior of the casing and to the display matter carried on the inner face of the panel. The lower channel member 7 is provided with a 10 stop 8 for limiting the movement of the panel in the direction of closing.

As a means for holding the display matter I have arranged on the inner surface of the panel B a plurality of spaced, parallel 15 channel bars 9 extending crosswise of the panel and across the middle opening 10 in the panel, thus forming guide-ways for receiving the display matter. It is to be noted that the cross bars 9 with the exception of 20 the upper and lower bars are formed of two channel bars placed back to back and secured together by soldering or other suitable means and have a stiffening bar 11 extending the length thereof and covering the 25 seam. This not only adds to the strength of the guide-ways but improves the outward appearance thereof. Referring more especially to Fig. 7, it will be seen that the channel bars are of sufficient width to accommodate the display matter, in this instance stencil sheets or strips 12 and the translucent members 13 preferably of glass, both 30 slidable in the channels 9 which are open at one end 14 for insertion of the stencil sheets and glass members, and closed at 35 their other ends by stop members 15, which prevent them from being slid past their proper position.

An opening 16 is provided at one side of 40 the casing and adjacent the panel B to give clearance for the protruding guide-ways 9 carried on the inner surface of the panel and through which the display matter and glasses may be inserted. In order to remove and 45 insert display sheets or glasses, different colored glasses being desirable for certain effects, it is only necessary to slide the panel very little for gaining access thereto. This opening 16 may be closed by means of the 50 combined closure and light seal 17 in the form of a sliding shutter having slotted engagement with the locking screws 18, whereby it may be locked in position. By reason of the ends of the channels 9 falling short 55 of the side of the box when the panel is in closed position, the combined closure and light seal serves to lock the panel in place when the closure 17 is in closed position. Hence it will be seen that the display matter 60 can not be easily tampered with by unauthorized persons.

The particular arrangement of the illuminating means will now be described. Arranged at vertically spaced intervals at each 65 side of the casing are a plurality of brackets

19 bolted or otherwise secured to the casing A, which brackets carry electric light sockets 20 and electric bulbs 21. The upper faces 22 of the brackets 19 are slightly inclined from the horizontal which causes the 70 longitudinal axes of the electric bulbs 21 to incline slightly from the vertical. The amount of such inclination is determined by the inclination of the upper faces 22 of the brackets 19. This inclination of the bulb 75 serves to distribute the light to good advantage, removes the bulb from too close proximity to the side of the box and makes for ready removal of the bulbs from their sockets without interference with the adjacent 80 brackets and bulbs.

In order to effectively distribute the light over all of the display matter I provide the reflector 23 at the bottom of and within the casing A which reflector extends horizontally thereof. Thus it will be seen that the light is reflected and uniformly distributed to the panel and without glare. 85

A similar reflector 24 is located in a compartment or head piece 25 secured to the top of the casing. The front of this compartment has a central opening 26 behind which is supported in guide-ways 27 a translucent member 28 bearing advertising matter which may be a general title for the 90 matter displayed in the other portion of the sign, as for instance the name of the theatre displaying its program. The reflector 24 distributes the light through the 95 translucent member 28. 100

It will be apparent from the above description that the construction of the panel and casing is such as will very well adapt itself to being built into the wall of a building with the panel B protruding a sufficient amount to allow sliding movement thereof for giving access to the interior of the casing and the display matter. 105

It will now be understood that when my invention is used for a theatre display sign, 110 stencil strips or some other form of strips in which the advertising will stand out when the sign is illuminated may be readily changed periodically that is to say the apparatus can be used continuously by merely changing the strips from week to week, so that the weekly program may be inexpensively changed, the only costs being that of the display strips. If desired colored 115 glasses may be used with good effect to cause some special feature of the program to stand out from the rest. The sign as a whole is very ornamental and attractive and therefore draws attention to it. 120

I claim:

1. A display sign comprising a casing, illuminating means within said casing, said casing formed of sheet metal having horizontal top and bottom walls and vertical 130 side walls forming a casing having an open

- front portion, stiff ribs upon said top and bottom walls located at the front edges of the latter, a panel adapted for closing the front of the casing having its outer edges 5 extending beyond and overlapping said top, bottom and side walls of the casing, said panel being of open frame construction, brackets located upon the rear surface of the top and bottom portions of said panel 10 adapted to embrace said stiff ribs of the casing and slide horizontally thereon, a series of horizontal guideways secured upon the rear face of said panel in parallel relation to said ribs of the casing, slides having display characters thereon, said slides 15 removably mounted in said horizontal guideways and visible through the open portion of the front panel, means upon the casing adapted for securing the front panel 20 in a fixed position in relation to the casing, and illuminating means within said casing.
2. A display sign comprising a sheet metal casing having a back, a top wall, a bottom wall, and a side wall equal in width to the 25 width of the top and bottom walls, a front panel having an open central portion slidably mounted upon said top and bottom walls, guideways upon the inner face of the front panel, a narrow side wall forming part of 30 said casing forming an opening between said narrow wall and the front panel through which said guideways may pass, a plate forming a shutter slidably mounted upon said narrow wall adapted to abut 35 against the inner face of the front panel and close said opening between said narrow wall and said panel, a slide having display characters thereon removably mounted in said guideways, and illuminating means within 40 said casing.
3. A display sign comprising a sheet metal casing having a back, a top wall, a bottom wall, and a side wall equal in width to the width of the top and bottom walls, a front 45 panel having an open central portion slidably mounted upon said top and bottom walls, guideways upon the inner face of the front panel, a narrow side wall forming part of said casing forming an opening between said narrow wall and the front panel through 50 which said guideways may pass, a plate forming a shutter slidably mounted upon said narrow wall, a stiffening edge portion formed upon said plate adapted to abut 55 against the inner face of the front panel and close said opening between said narrow wall and said panel, a slide having display characters thereon removably mounted in said guideways, and illuminating means within 60 said casing.
4. A display sign including in combination a casing having illuminating means therein, said casing having a back, side walls, a top wall and a bottom wall, a panel mounted 65 upon the front face of said casing, one of
- said side walls of the casing being of narrow formation and forming a vertical opening between said narrow wall and the front panel, a series of guide-ways upon the inner face of the front panel, slides adapted for carrying display advertising characters 70 slidably horizontally in said guide-ways and adapted to pass through said vertical opening, a plate mounted upon said narrow side wall of the casing and slidable in a plane parallel with said last mentioned wall 75 adapted to form a shutter for closing said vertical opening, and a fastening device for securing said plate in a closed position upon said last mentioned wall. 80
5. A display sign comprising a sheet metal casing having a back, a top wall, a bottom wall, and a side wall equal in width to the width of the top and bottom walls, a front panel having an open central portion slidably mounted upon said top and bottom walls, 85 guideways upon the inner face of the front panel, a narrow side wall forming part of said casing forming an opening between said narrow wall and the front panel through 90 which said guideways may pass, a plate forming a shutter slidably mounted upon said narrow wall, a plate having elongated slots formed therein, and fastening devices upon said narrow wall extending through 95 the slotted portion of said plate and upon which said plate is slidably mounted in a plane parallel with said narrow wall adapted for closing the opening between said narrow wall and said panel. 100
6. A display sign comprising a casing, internal illuminating means within the casing, said casing formed of sheet metal provided with top and bottom walls, the bottom wall having a portion projecting downwardly, forwardly and upwardly forming a stiff rib, the top wall having a portion projecting upwardly, forwardly and downwardly, and forming a stiff rib, a panel for closing the front of the casing, a bracket upon the upper portion of said panel adapted to embrace the upper stiff rib of the casing, and a lower bracket upon said panel adapted to embrace the lower stiff rib of the casing and slidably connecting the panel to the casing to permit it to be removed laterally therefrom, and means for mounting advertising characters upon said panel. 105
7. A display sign comprising a casing, internal illuminating means within the casing, said casing formed of sheet metal provided with top and bottom walls, the bottom wall having a portion projecting downwardly, forwardly and upwardly forming a stiff rib, the top wall having a portion projecting upwardly, forwardly and downwardly and forming a stiff rib, a panel of 110 rectangular construction having an open central portion adapted to be occupied with ad-

vertising characters, said frame being of larger dimensions than the front face of the casing and adapted to overlap said ribs, said frame having its inner face positioned against said upwardly and downwardly portions of said ribs of the casing, and brackets upon the upper and lower portions of the

panel adapted to embrace the ribs upon the upper and lower walls of the casing upon which ribs said panel is adapted to slide. 10

In testimony whereof, I affix my signature hereto.

SIMON LIBROS.
